UNITED STATES PATENT OFFICE

WALTER C. TROUT, OF LUFKIN, TEXAS

WALKING BEAM HEAD YOKE

Application filed October 22, 1928. Serial No. 314,118.

My invention relates to an improvement in the head yoke which is attached to the walking beam used on standard rigs in well drilling and pumping equipment.

The walking beam is used in drilling and pumping equipment to transpose the rotary motion of the source of power into vertical reciprocating motion, the ends of the walking beam require attachments thereto in order that the various operations may be conveniently performed. In either drilling or pumping, the walking beam must exert an upward pull upon the drill cable or the polish rod and there must accordingly be a suitable connection of the cable to the walking beam. It is to this connecting member that my improvement appertains.

It is an object of my invention to provide a sturdy cable carrying member or head upon the walking beam so that a heavy pull may be exerted upon the cable without mutilating it.

Another object is to construct my improved head yoke so that the ordinary T head bearing is retained upon the walking beam for use when my improvement is not employed.

A further object is to form an arcuate guide member in combination with my head so that a vertical pull is at all times exerted upon the cable, and which may be folded to an inoperative position.

I have also shown an improved walking beam to which the head is attached.

My improvement embodies other novel features which will be apparent to those skilled in the art to which it relates when the following description is considered in connection with the drawings wherein:

Fig. 1 shows a side elevation of a walking beam having my improvement applied thereto.

Fig. 2 is a bottom plan view showing the construction of the walking beam.

Fig. 3 is an enlarged side elevation of the head yoke showing the cable threaded therein.

Fig. 4 is a section on the line 4—4 of Fig. 3 and shows the construction of the head yoke for attachment to the walking beam.

Fig. 5 is a front elevation of the combined

head yoke and guide members in operative position upon the walking beam.

The walking beam is indicated generally by the numeral 1 and may comprise I beams or channel members, as shown at 2 and 3 in Fig. 5. These longitudinal members are connected by web plates 4 and 5 disposed on the upper and lower sides thereof and extending substantially thruout their length. The walking beam is braced, to give it the necessary rigidity, by means of an upright 7 fixed upon the plate 4 and having a plurality of tie bars 8 extending to the ends of the beam. By this construction a substantial truss structure is procured which will withstand heavy strains and is not exceedingly heavy, or cumbersome. Beneath the upright 7 is the usual center bearing 10 whereby the walking beam is pivotally supported on the Samson post, not shown.

With reference to Fig. 1, 15 indicates the usual T-head bearing provided upon the end of the walking beam and it is usual to suspend from this bearing a temper screw to grip the drill cable, or an adjuster block to retain the polish rod, but in either case a trunnion of usual construction rests in the T head bearing 15. With a structure using the T head bearing a truly vertical reciprocation of the cable or polish rod was impossible as the walking beam, in pivoting, traveled in the arc of a circle and this imparted some lateral movement to the T-bearing. This is especially objectionable with the polish rod as it flexed the rod when it passed thru the stuffing box at the tubing head and resulted in wear and displacement of the packing. However, the T-head bearing is desirable for some operations and I have accordingly retained it for use when my head yoke is not employed.

In order that my improvement may be readily attached to the walking beam I have formed the head yoke 17 preferably as a casting or stamping which has a base 18, fins 19, and cable supporting groove 23. As shown in Fig. 4, the base 18 has a plurality of openings whereby it may be riveted or bolted to the members 2 and 3 and has outstanding ears 20 which have a cable groove 21 formed therein. A central opening 22 is provided

to permit the use of a connection to the **T**-bearing, if desired. The head 17 has the cable groove, with side flanges 21 passing up the face, as shown in Fig. 5, but adjacent to the top they curve slightly into the head to form a groove with vertical flanges 23, from which the cable 24 may not readily be displaced. The face of the block 17 is arcuate, being formed as an arc of the circumference 10 of the circle having its center in the center iron 10. The ears 20 extend below the base 18 and embrace the bearing 15, thus providing a continuous support for the cable 24. The flanges 21 may be cut away slightly as 15 at 25 to allow access to the bearing 15. It will be seen that the head yoke just described 20 so positioned with respect to the **T**-head bearing 15 that the thrust of the load carried by either one will be approximately in the same vertical plane, as best seen in Fig. 3.

In combination with the head yoke 17 just described, I have provided a guide structure 30 for the cable 24 so that on the upward swing of the walking beam the point of contact of the cable will be maintained in a vertical position. This guide structure is of 30 arcuate form, the same as the head 17, and is shown as constructed of two angles 31 connected with brackets 32 which are in turn pivoted at 34 to the walking beam 1, thru the members 2 and 3 and the anchor plates 33, which are fixed on the walking beam. To support the guide structure, a brace arm 35 is pivoted to the under side of the walking beam as at 36 and detachably connected to the guide at 37. Thus by detaching the arm 40 at 37 it may be folded or swung back under the walking beam so that it will not interfere with the operation, when the **T**-bearing 15 is to be used. The angles 31 form a continuation of the groove 21 and converge to- 45 ward each other in order that the cable 24 will approach the adjuster block or other gripping device in the proper direction.

The particular construction of my yoke and guide for attachment to the walking beam results in a very effective and convenient hanger for the cable, and the device is also simple and economical to construct.

It is common practice in drilling and pumping to loop a short piece of cable over 50 the end of the walking beam and connect it to either the temper screw or the adjuster block and thus dispense with the use of the **T** bearing. With my improved head yoke and guide, however, a truly vertical move- 55 ment is assured due to the arcuate formation of the parts and the cable may be quickly detached, if desired.

Having described my invention, what I desire to secure by Letters Patent is:—

60 1. A head yoke for walking beams includ-

ing a portion adapted to seat on the walking beam, a grooved cable supporting portion thereon, and means formed in said yoke to receive a portion of a **T** head bearing carried by said beam.

2. A walking beam, a **T** head bearing thereon to receive a temper screw or adjuster block, a head yoke on said beam to receive a support cable, and means formed in said head yoke to receive said bearing so that the thrust on either said bearing or yoke will be in the same vertical plane.

In testimony whereof I hereunto affix my signature this 15th day of October, A. D. 1928.

WALTER C. TROUT.
